[57] CLAIM

The ornamental design for a bar, as shown and described.

DESCRIPTION

FIG. 1 is a front elevational view of a bar showing my new design;

FIG. 2 is a top plan view thereof;

FIG. 3 is a rear elevational view thereof;

FIG. 4 is an end elevational view thereof, the opposite end being substantially a mirror image thereof; and
FIG. 5 is a top plan view thereof, top of the bar removed along line 5—5 of FIG. 1 for convenience of illustration.

FIG. 1

FIG. 2

FIG. 3

FIG. 4

FIG. 5
